UNITED STATES PATENT OFFICE.

WILLIS D. BEAMER AND JAMES FRANK DUFFY, OF CHICAGO, ILLINOIS.

CARBURETER.

1,131,312.

Specification of Letters Patent.

Patented Mar. 9, 1915.

Application filed December 26, 1913. Serial No. 308,847.

To all whom it may concern:

Be it known that we, WILLIS D. BEAMER and JAMES FRANK DUFFY, both citizens of the United States, residing at Chicago, county of Cook, and State of Illinois, have invented certain new and useful Improvements in Carbureters, of which the following is a specification:

The present invention relates to the type of carbureter designed and adapted for the generation of explosive mixture to be used in gas engines.

The objects of the present invention are to design a carbureter which will, by proper manipulation, enable the production of the proper and desired mixture under varying circumstances and conditions of operation; to obtain a uniform grade of mixture at all times, but to vary the quantity according to the load on the engine; and to obtain the above result by varying the relation of the area of the throat of the venturi with respect to the degree which the manifold or throttle valve is opened, and to provide a connection between the means for varying the area of the throat of the venturi and the manifold or throttle valve, whereby said area varying means and throttle will be actuated in unison to maintain at various periods certain relative degrees of opening between them.

Further objects of the invention are to so configure the means for varying the area of the throat of the venturi, whereby curvilinear walls will always be maintained about said throat; and to arrange the means for varying the size of the Venturi throat and for controlling the point of discharge from the venturi whereby they operate freely and easily, and to provide means whereby the throat area varying means may be changed without changing the size of the opening at the point of discharge of the venturi.

The invention further consists in the features of construction and combinations of parts hereinafter described and claimed.

In the drawings: Figure 1 is an elevation of the carbureter of the present invention; Fig. 2 is a view showing the mixing portion of the carbureter in section with the float chamber in elevation; Fig. 3 is a horizontal section through the members for controlling the outlet of the venturi, with the float casing broken off; Fig. 4 is a horizontal section through the members which vary the area of the throat of the venturi, with the float cas-

ing broken off; Fig. 5 is an elevation of one of the members for varying the area of the Venturi throat; and Figs. 6, 7, 8, 9, 10, 11, 12, 13, 14, and 15 are diagrammatic views showing the relative positions assumed by the members which vary the area of the Venturi throat and the members which control the discharge end of the venturi during different positions of operations; and Figs. 16 and 17 details of the connection between the crank 47 and link 54 to get an adjustment therebetween.

In the art to which the present invention relates, various means have been employed looking toward the production of a mixture which will prove satisfactory under the varying conditions of operation. The present invention aims to maintain a uniform grade of mixture and to vary the quantity as the load of the engine is increased or decreased, and deals with a mechanism seeking to accomplish this result which is brought about by varying the area of the throat of the venturi in correspondence to the size of the opening at the point of discharge of the venturi, and to change such variation according to the manner and conditions under which the engine is operating.

Referring now to the drawings, and particularly to Fig. 1, the carbureter, as shown, consists of a casing 16 which may be termed the mixing casing, and a casing 17 which may be termed the float casing. These casings, as shown, are joined together by a web 18. As respects the particular sort of float mechanism employed, that is immaterial to the present invention, and hence no detailed description will be given of this in the present application. It is sufficient to say that any suitable float mechanism may be employed.

A passage 19 is formed in a block 20, by which gasoline or other fuel is led into a chamber or pocket 21 in the casing 16, and this pocket communicates with the bore of a nozzle 22 of any suitable construction. The nozzle 22 has its discharge end located adjacent the throat 23 of a Venturi tube or passage 24. The outlet end of said tube or passage is at 25 and the inlet end at 26. The inlet end has communication by suitable means with the outside air. The casing 16 is provided with a head or flange 27 which may be secured in any suitable manner to the manifold leading to the engine. In fact,

the discharge end of the venturi may be termed the "manifold" or "engine end" thereof.

As stated, the primary object of the present invention is to secure a proper mixture under the varying conditions of operation of the engine. This is done by changing the area of the throat of the venturi in correspondence to the size of the opening at the 10 point of discharge from the venturi.

The control for the discharge of the venturi in the construction shown consists of throttle valve members 28 and 29 which are of a cylindrical character, and each of the 15 valve members is provided with a semi-circular opening. The opening in the valve member 28 is designated by the numeral 30, and that in the member 29 by the numeral 31. As shown in Fig. 2, when these openings 20 are brought in direct opposed relation to one another, an opening of maximum size is provided at the discharge of the Venturi tube. The walls of the openings 30 and 31 are slightly beveled, as shown in Fig. 2, 25 to conform to the taper of the venturi.

In the construction shown, each of the members 28 and 29 has a flattened portion as at 32 to provide the necessary engaging 30 surface when they are brought together, and to obtain the desired fit between the members when they are brought together, which fit would be difficult to obtain if the members were entirely cylindrical. Each of the members 28 and 29 are mounted to rotate 35 in the casing 16, as better shown perhaps in Fig. 3, and the member 28 is provided with trunnions 34 and the member 29 with trunnions 35, the members being locked in place, in the construction shown, by plates 36 and 40 37 secured in any suitable manner by detachable fasteners to the body of the casing 16.

The means for varying the area of the throat of the venturi is shown perhaps more 45 clearly in Figs. 2 and 4. These members are designated by the numerals 38 and 39 and are similar in formation to one another, and one of them is shown in elevation in Fig. 5 of the drawings. These members consist of 50 a body 40 cut away to provide an opening 41, said opening being of a tapering character and of less width at the top 42 than at the bottom 43, and what may be termed the rear wall 44 of the opening is of a convex 55 nature, as will be seen in Fig. 2. The side walls 45 of the opening 41 are shown more clearly in Fig. 5, and as will be seen are of an undulating diverging character from top to bottom giving to the opening the property of tapering from top to bottom. As 60 shown in Fig. 2, one of these members lies upon each side of the throat of the venturi and may be said to constitute the walls of said throat. The members are mounted to 65 rotate within the casing 16 and are locked

in position, as shown in Fig. 4 by the plates 36 and 37.

A connection is provided between the members 28, 29, 38 and 39, which connection consists of a crank 46 joined to the trunnion 70 34 of the member 28, and a crank 47 joined to the trunnion 35 of the member 29, which cranks are connected by a link 48, a crank 49 joined to the trunnion 50 of the member 38, and a crank 51 joined to the trunnion 52 75 of the member 39. The last two mentioned cranks are connected as at 53 in Fig. 1 by a slot and pin connection. The crank 51 is attached to a link 54 which is adjustable in and out to vary the relative positions between the cranks 51 and 49 as respects the cranks 47 and 46, the reason for which will be more clearly hereinafter explained. It is expressly understood, however, that the foregoing described connection between the 85 members 28, 29, 38, and 39 only describes one method of obtaining a practical connection between these members and this particular connection may be changed without departing from the spirit of the present invention. The connection above described constitutes one means for actuating the members 28 and 29 simultaneously with the members 38 and 39, and any suitable means may be provided for actuating this connection from any convenient or desirable location that is proper.

The foregoing constitutes a description of the elements and parts which form the mechanism of the present invention. We will now refer to the various positions assumed by these parts, which will be clearly understood, it is thought, from a study of Figs. 6 to 15 inclusive, which show the various positions assumed in a diagrammatic manner. Referring first to Fig. 7, as there shown, the members 38 and 39 have been moved to a position whereby the area of the throat of the venturi is of a minimum size, and the opening in the throat is indicated by the 110 numeral 55. The members 28 and 29 have been moved so that there is but a slight opening 56 between them, and the discharge end of the venturi is thus nearly closed. This position of the parts is brought about 115 when the engine is idling. That is, simply running as slow as possible without any load. In this position, the size of the opening 55 through the throat of the venturi is cut down, and the opening 56 being restricted, there will be but a small suctional force 120 exerted in the venturi. Therefore, the quantity of air forced through the venturi will be relatively small. This small suctional force draws out a relatively small quantity of 125 gasoline, thus producing a relatively small quantity of mixture of the desired proportions of gasoline and air. To summarize, there will be a suctional force exerted at the discharge end of the nozzle 22 capable of 130

drawing some gasoline therefrom, while the amount of air with which said gasoline is mixed will be relatively small, whereby a mixture will result which will be of the proper proportions of gasoline and air, but which will be of a relatively small quantity as is proper. This is the quantity of mixture which is desired under these circumstances. The relation of the opening 55 to the opening 56 is also shown in Fig. 6.

Now referring to Figs. 8 and 9, the parts controlling the area of the venturi throat and the point of discharge of the venturi are shown in a position they would assume when the engine is running under a light load. Under this condition, it will be observed that the parts are so positioned that the size of the opening at the throat of the venturi indicated by the numeral 57 is somewhat increased over the size of the opening 55, and that the size of the opening 58 between the members 28 and 29 is increased over the size of the opening 56. Under these conditions, there will be a greater suction exerted in the venturi owing to the increase in the size of the opening 58 at the throttle. There will thus be a greater amount of suction exerted in the venturi than in the case of Figs. 6 and 7. It will be also observed that the area of the throat of the venturi has been increased. Therefore, there will be a greater volume of air passing through the venturi, and there will be a greater suctional force at the discharge end of the gasoline nozzle. There will thus be more air and more gasoline drawn through the venturi than in the case of Figs. 6 and 7. The proportion of air to gasoline, however, will be the same to all practical purposes, and the increase in the size of the throttle opening and the size of the throat of the venturi will merely result in a greater quantity of mixture being supplied to the engine, although the mixture will be substantially the same proportion as in the case of Figs. 6 and 7.

Now referring to Figs. 10 and 11 with the parts in this position, the load on the engine has been increased. The opening at the throat of the venturi is indicated by the numeral 59, and the opening at the point of discharge of the venturi is indicated by the numeral 60. Under these conditions, both openings will be increased and there will be more gasoline and air supplied than in the two previous instances. The relation of gasoline to air, however, will remain the same to all practical purposes, and hence there will be simply an increase in the volume of mixture supplied into the cylinder of the engine.

Referring to Figs. 12 and 13, the opening in the throat of the venturi is indicated by the numeral 61, and the opening at the point of discharge of the venturi, or the

throttle opening by the numeral 62. In this instance, for the reason previously explained, there will be a greater quantity of mixture than in all previous cases, but of substantially the same proportions of air to gasoline.

Referring to Figs. 14 and 15, this shows the parts fully open. The opening at the throat of the venturi is indicated by the numeral 63, and the throttle opening by the numeral 64. In this instance, as will be readily understood there will be a still greater quantity of mixture supplied into the engine than in any previous instance, but the mixture will be of the same general proportions as respects air and gasoline. It will thus be apparent that by the arrangement of the mechanism described, various quantities of mixture are supplied to the engine as is needed in correspondence to the load which the engine is carrying. The character of the mixture remains substantially the same. That is, the correct character for efficient combustion.

It has been found in practice that carburetors require a different adjustment in cold weather than in hot weather; that is, they should be adjusted to accommodate themselves to different climatic conditions. To accomplish this, in the structure shown, a member 65 is employed which is simply a thumb-screw, and which acts to force the link 54 back and forth changing the relative positions of the cranks 51 and 49, as respects the cranks 46 and 47, whereby the members 38 and 39 are adjusted to change their relation; that is, the members 38 and 39 are moved in a manner whereby the opening, through the throat of the venturi, is changed independent of any change in the throttle opening. This will give the desired proportions of air to gasoline and will produce the desired mixture.

A suitable means of connecting the link 54 with the crank 47 is illustrated in Figs. 16 and 17 and consists of a pin 66 which is carried by the crank and enters a curved slot 67 in the link 54. The curve of this slot is preferably struck on a radius from the axial center of the crank 47. The threaded stem 65 extends through an upper enlarged head upon the pin 66 and this stem has a finger piece which rests against a lip 68 extending from the link 54. When the link 54 moves it will move the pin 66 owing to the connection between the stem 65 and the pin, and the stem 65 and the link, and yet an adjustment can be readily made of the crank 47 without affecting the position of the link 54 and crank 51, owing to the slot 67.

By the configuration employed in the members 38 and 39, said members, when turned to their various positions, always cooperate to maintain a curvilinear wall about the throat of the venturi which allows the

42
air to pass through said throat without undue obstruction.

Although the device has been described with considerable particularity, it is understood that changes or modifications may be made, and that it is not the intention to limit the invention in any other manner than by the terms of the appended claims.

We claim:

10 1. In a carbureter the combination of a casing having a passage therethrough embodying a Venturi tube, a nozzle having its open end located adjacent the throat of said tube, means for controlling the outlet from 15 said passage, means for varying the area of said Venturi throat, a crank for operating said outlet controlling means, a crank for operating said throat area varying means, a link connecting said cranks and means for 20 longitudinally moving said link to adjust the position of said throat area varying means independent of actuating said outlet controlling means whereby a mixture is produced in accordance with the climatic 25 requirements, substantially as described.

2. In a carbureter the combination of a casing having a passage therethrough embodying a Venturi tube, companion rollers mounted in the walls of said passage and 30 lying partially within said walls and partially within said passage, each of said rollers being cut away to form an opening therebetween, the walls surrounding said cut-away portion being configured to form 35 the throat of the Venturi tube, and to form a portion of the wall of the passage when the rollers are moved to establish the maximum throat area, means for actuating said 40 rollers in unison to vary the size of the Venturi throat area, a spray nozzle extending into the opening between the rollers, means for controlling the manifold end of 45 the casing passage to vary the area of the passage at that point, and a connection between the roller actuating means and manifold end controlling means to operate them in unison, substantially as described.

3. In a carbureter the combination of a casing having a passage therein embodying 50 a Venturi tube, companion rollers mounted in the walls of said passage and lying partially within said passage, each of said rollers being cut away at oppositely disposed points to form an opening between the 55 roller, said cuts producing concavo-convex walls about said opening, the convex portion forming the throat of said Venturi

tube, means for actuating said rollers in unison to vary the size of the Venturi throat opening, a spray nozzle extending into the opening between the rollers, means for controlling the manifold end of the casing passage to vary the area of the passage at that point, and a connection between the roller actuating means and manifold end controlling means to operate them in unison, substantially as described.

4. In a carbureter the combination of a casing having a passage therein embodying a Venturi tube, companion rollers mounted in the walls of said passage and lying partially within said walls and partially within said passage, each of said rollers being cut away at oppositely disposed points to form a passage therebetween, said cuts producing concave-convex walls surrounding said roller passage with the convex portion forming the throat of the venturi, the width of the cuts above the convex portion being less than the width of the cut below the convex portion, means for actuating said rollers in unison to vary the size of the Venturi throat, a spray nozzle extending into the opening between the rollers, means for controlling the manifold end of the casing passage to vary the area of the passage at that point, and a connection between the roller actuating means and manifold end controlling means to operate them in unison, substantially as described.

5. In a carbureter the combination of a casing having a passage therein embodying a Venturi tube, companion rollers having portions thereof configured to form the throat of the Venturi passage, companion rollers located adjacent the manifold end of said passage and mounted in the walls of the passage and extending partially within said walls and partially within said passage and cut away to form the manifold passage of the casing, and a connection between the rollers located at the throat of the venturi and the rollers located adjacent the manifold end of the case passage whereby they are operated in unison to vary the area of the throat and simultaneously vary the area of the manifold opening, substantially as described.
